UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WEFT FEELER-TIP FOR LOOMS.

1,380,940.

Specification of Letters Patent.

Patented June 7, 1921.

Application filed August 7, 1920. Serial No. 401,943.

To all whom it may concern:

Be it known that I, EDWARD S. STIMPSON, of Hopedale, in the county of Worcester and State of Massachusetts, have invented a new 5 Weft Feeler-Tip for Looms, of which the following is a specification.

The present invention is an improvement upon the feeler mechanism set forth in my United States Letters Patent No. 1,309,226, 10 July 8, 1919, and consists in the feeler tip construction.

In the type of laterally sliding feeler disclosed in said patent, it is important that the teeth of the feeler tip should cling to the 15 weft so as to prevent premature side slipping under all conditions of the weft winding. Unless this is the case the bobbins may be ejected while still carrying a large amount of weft. At the same time, the teeth must 20 freely and with certainty slip along the bare bobbin so that the functional side slip will take place when demanded. Also, the tip organization should be such that the weft will not be cut and that the bobbin will not 25 be scratched or marred.

The present invention relates to such a construction of the tip that it will adequately cling to the weft when in contact therewith, and will slip reliably upon the bare bobbin 30 without scratching or marring the same.

The improvement is illustrated in the accompanying drawings, in which—

Figure 1, is a plan view of the feeler mechanism. Fig. 2, is a plan view of the feeler tip on an enlarged scale. Fig. 3 is a plan view of the feeler tip on an enlarged scale 35 illustrating the side slip of the tip on the bare surface of a bobbin. Fig. 4 is a vertical section in the plane indicated by the line 40 4—4 in Fig. 2. Fig. 5 is a view looking at the weft contacting face of the feeler tip.

The side slipping feeler arm A is similar in construction and mode of operation to that of the feeler arm set forth in the afore- 45 said Patent No. 1,309,226. The present improvement relates solely to the feeler tip B.

The feeler tip is an integral portion of the feeler arm and it constitutes the weft feeling end of said arm. The weft feeling 50 face of the feeler tip is curved in a horizontal direction so as to be convex toward the weft bobbin as shown in the plan views of Figs. 2 and 3. Also, in vertical planes the weft contacting surface of the tip is likewise 55 curved and convex toward the bobbin as

illustrated in Fig. 4. In other words, the rear end of the weft contacting face of the feeler tip is convex toward the weft and bobbin both horizontally and vertically. The weft contacting face of the feeler tip 60 is composed of a plurality of weft engaging teeth C integral with the tip and hence with the feeler arm. These teeth are formed by slits D in the weft contacting face of the tip. These slits are inclined with respect to the 65 upper and lower surface of the tip, as shown in Fig. 5, and are such as would be made by a saw with flat parallel sides. The result is that each tooth C is blunt along horizontal lines, it is pointed along vertical lines due 70 to the convexity of the rear end of the tip, it is inclined between top and bottom, and it has square edges.

Owing to the horizontal convexity of the feeler tip, as shown in Figs. 2 and 3, the 75 rear weft contacting ends of the teeth are arranged in a horizontally extending arc of a circle, so that the rear ends of the teeth are at varying distances from the cylindrical surface of the bobbin or other weft carrier, 80 as illustrated in Fig. 3. In the normal position of the feeler arm, shown in Figs. 1 and 2, the middle teeth of the tip are nearer the axis of the bobbin than the teeth at either end of the horizontally extending arc. 85

The effect of this tooth construction is that the teeth sink into the mass of the weft along both horizontal and vertical lines as exaggeratedly shown in Figs. 2 and 4 respectively. Hence, when the weft E is present 90 the teeth cling to the weft and prevent the feeler arm moving laterally under the impact or frontward push of the bobbin F. The teeth cannot cut the weft because they are blunt and because they extend diagonally so that no one tooth can enter between 95 parallel convolutions of the weft on the bobbin.

At the same time, when the bobbin is bare where it contacts with the tip, the tip slips 100 laterally along the bare surface due to the impact of the bobbin, as illustrated in Fig. 3. This slip takes place with certainty and without any scratching or marring of the bobbin, since the teeth rock as well as slip 105 on the bobbin.

Fig. 1 illustrates the weft just making initial contact with the feeler tip and also shows parts of the feeler mechanism which immediately coöperate with the feeler arm. 110

These coöperating feeler parts are the same as those of the aforesaid Patent No. 1,309,226. It now suffices to say that the feeler arm is moved forwardly by the impact of the bobbin or other weft carrier, and it is moved rearwardly by a spring G. When the feeler arm slides laterally, as indicated in Fig. 3, a controller H is moved laterally thereby initiating the action of the weft replenishing mechanism as fully set forth in the aforesaid patent thereby effecting the replenishing of weft before the running weft is completely exhausted.

I claim—

15. 1. A feeler having its weft contacting end convex toward the bobbin both vertically and horizontally, said weft contacting end having a plurality of integral teeth arranged in a horizontally extending curve, 20 said teeth being constituted by slits in the weft contacting end of the feeler extending diagonally from the top to the bottom of

the feeler whereby teeth are formed integral with the feeler and having blunt rear and square edges and extending diagonally from 25 the top to the bottom of the feeler.

2. A feeler arm having at its weft contacting end a plurality of integral teeth, said teeth being constituted by slits in the rear end of the feeler tip extending diagonally from the top to the bottom of the feeler.

3. A feeler having its feeling end curved in a horizontal direction, said feeling end having a plurality of teeth, each of which 35 extends diagonally from the top to the bottom of the feeler.

4. A feeler having a plurality of teeth at its feeling or contacting end, each of said teeth extending diagonally from the top to 40 the bottom of the feeler.

In witness whereof, I have hereunto signed my name.

EDWARD S. STIMPSON.
